ADJUSTABLE NOZZLE

Ho Chow, Yonkers, N.Y., assignor, by mesne assignments,
to International Patent Research Corp., New York,
N.Y., a corporation of New York

Filed Feb. 28, 1961, Ser. No. 92,303

3 Claims. (Cl. 239—456)

The present invention relates to an adjustable nozzle specifically designed to be attached to a hose and to be used for such purposes as the sprinkling of lawns, and in its more specific aspects relates to an adjustable nozzle of the gun type.

The primary object of the present invention is to devise a nozzle assembly which will permit ready and positive control of the type of spray emanating from the nozzle, which will be reliable and relatively foolproof in operation, yet which will be inexpensive to manufacture.

Inexpensiveness is usually antithetical to quality. However, by reason of the novel nozzle design here disclosed the usual conflict between those two factors has to a large extent been resolved. Indeed, to some extent the very facts which make for the inexpensiveness of the nozzle design here disclosed also contribute markedly to its superior performance. For example, the use of a minimal number of parts, as here disclosed, both facilitates manufacture and improves operation. The use of a multiplicity of parts complicates assembly and thus adds greatly to manufacturing expense. A multiplicity of parts usually produces leakage problems, and requires manufacture to close tolerances, thus further increasing cost. The greater the number of parts the greater is the liability to malfunction.

When a device is easy to assemble, it is often just as easy to disassemble, and this will interfere with its use, particularly where, as is the case here, manipulation of one of the assembled parts is constantly required during the use of the product if it is to perform its desired function. The design of the instant invention maintains the advantages of easy assembly and avoids its usual disadvantages.

In accordance with the instant invention, an exceedingly simple structure, which may be composed of as few as three parts, will function as an adjustable nozzle with fully the same facility and reliability as much more complex prior art structures. The parts are so designed that assembly during manufacture is facilitated and accidental disassembly during use is reliably and positively prevented.

To these ends the nozzle comprises an outer body, which is preferably unitary in nature, and a single valve member, also preferably unitary in nature, which is movably received within the body and which cooperates therewith to control the nature of the fluid stream permitted to escape from the body. This valve member has a part which extends out through an opening in the body and which is accessible for manual rotation, to adjust the nozzle. The valve member and the body are provided with cooperatively engaging threaded portions, so that as the externally extending part of the valve member is rotated the valve member will also move axially through the body, thereby to accomplish its adjustment feature. Escape of fluid through the body opening which receives the outwardly extending valve member part is prevented by means of a sealing ring received within registering grooves in the body and the valve member respectively, at least one of those grooves being axially elongated so as to permit the valve member to move through its adjusting positions without adversely affecting the sealing effect of the ring. The parts are so arranged that threaded engagement between the valve member and the body is initiated before the sealing ring and the grooves with which that

2

ring is to cooperate assume their operative sealing relationship. Screwing of the valve member into the body brings these parts into their sealing relationship, the structure of the parts being such as to facilitate this movement. Once the sealing ring is operatively received in both the groove in the body and the groove in the valve member, the construction of those grooves is such as to strongly inhibit escape of the sealing ring from those grooves, thereby effectively preventing accidental disassembly of the parts and providing a positive stop for the valve member at at least one of its extreme operative positions. The structure is such that the valve member is at all times properly located, supported and guided within the nozzle body. The parts are sturdy, and need not be manufactured to any great degree of precision.

To the accomplishment of the above, and to such other objects as may hereinafter appear, the present invention relates to the construction of an adjustable nozzle as defined in the appended claims and as described in this specification, taken together with the accompanying drawings, in which:

FIG. 1 is a side elevational view of a preferred embodiment;

FIG. 2 is a fragmentary front elevational view thereof;

FIG. 3 is a fragmentary rear elevational view thereof; and

FIG. 4 is a cross sectional view of the entire nozzle, a part thereof being broken away, taken along the line 4—4 of FIG. 2.

30 The nozzle body, generally designated A, may be formed in one piece, as by die casting of metal or plastic. It comprises a substantially horizontal portion 2 having a horizontally extending bore 4 with an exit opening 6 at one end and another and larger opening 8 at the other end. Extending downwardly at an angle from the horizontal body portion 2 is a handle portion 10 having a passage 12 formed therein which communicates between the bore 4 and a hose-receiving internally threaded socket portion 14, a sealing ring 16 being received within a 35 groove 18 at the socket portion 14.

The walls of the bore 4 just to the rear of the relatively restricted exit opening 6 are tapered rearwardly and outwardly at 20, to define a valve seat. The bore 4, extending to the right from the walls 20 as viewed in FIG. 45 4, comprises a smooth-walled cylindrical section 22, followed by a section 24, opposite the passage 12, in which a fairly coarse internal thread 26 is formed. Axially to the right of the internally threaded section 24 is, in order, a cylindrical section 28, a ring-shaped internal groove 50 30 extending completely around the interior of the bore 4, and the rear opening 8, the axially outer portion of that opening 8 being axially and radially outwardly tapered at 8a. The side walls of the groove 30 are radially disposed, therefore being abruptly oriented relative 55 to the bottom wall of the groove 30.

The valve member, generally designated B, comprises, reading left to right as viewed in FIG. 4, a front tip part 32 movable through the exit opening 6, a rear tip part 34 having tapered walls adapted to engage with the bore surfaces 20 when the valve member B is appropriately positioned, a forward shaft part 36 provided with a plurality of radial extensions 38 the outer surfaces of which are adapted to slidably engage with the inner surface of the bore section 22, a rear shaft part 40 which 60 carries an external thread 42 which cooperates with the internal thread 26 in the bore 4, and a portion generally designated 44 of enlarged radius which extends out with clearance through the opening 8 in the body 2 and which carries, at its outwardly extending end, a handle or knob 46. The axial inner end of the part 44 is provided with an axially and radially outwardly tapered surface 48 and with an external ring-like groove 50 which is axially

elongated and which has substantially radially extending side walls which are therefore abruptly oriented relative to the bottom wall of the groove 50. The valve member B is preferably unitary in nature, and may be molded or die cast of metal or plastic.

The only other part of the nozzle is a resilient sealing ring 52 of a size such as to be simultaneously received within the grooves 30 and 50 and, when thus received, to sealingly engage the bottom walls of those grooves and thus prevent leakage of fluid therefrom.

Assembly of the nozzle of the present invention is simple in the extreme. The sealing ring 52 is first put into place either in the ring 30 or in the ring 50. If it is to be put in place in the ring 30 it is pushed through the rear opening 8 in the body 2, the inclined walls 8a facilitating this action. If it is to be put in place in the groove 50 it is slid over the left hand end of the valve member B into the groove 50, the inclined surface 48 facilitating this action. The valve member B is then inserted into the bore 4 through the opening 8 until the externally threaded portion 42 engages with the internally threaded portion 26. This will preferably be when the valve member A is axially positioned with the projections 38 received within the bore section 22, thus supporting and centering the left hand end of the valve member B, and before the enlarged valve member portion 44 with its groove 50 has entered the opening 8. Hence, whether the sealing ring 52 is in the groove 30 or the groove 50, it will not at this point be compressed.

Next the valve member B is screwed into the body 4, 30 the threaded engagement between the threads 42 and 26 developing a strong force moving the valve member B to the left. This force will be sufficient, when the sealing ring 52 is engaged and compressed either by the valve member part 44 (if the ring was initially in the groove 30) or by the body opening 8 (if the ring 52 was originally in the groove 50), and in combination with the tapered surface 48 or the tapered surface 8a respectively, to compress the sealing ring 52 and permit the groove 50 to move into registration with the groove 30, after which the sealing ring 52 will resume its normal shape, engaging the bottom walls of both grooves 30 and 50, and will seal the opening 8 and prevent the escape of any fluid therethrough.

The function of the inclined surfaces 48 or 8a in this connection is very important. It is by reason of the inclination of those surfaces that compression of the ring 52 is effected during assembly of the body A and valve member B. It has been pointed out that the side walls of the grooves 30 and 50 are not inclined as are surfaces 48 and 8a, but are instead abruptly oriented relative to their respective bottom walls. Consequently, any attempt to unscrew the valve member B after it has been properly assembled with the body A will be strongly resisted by the ring 52. (See FIG. 4, showing the valve member B in its extreme right hand position, with the sealing ring 52 engaging the left hand side wall of groove 50 and the right hand side wall of groove 30 and thus preventing further movement of the valve member B to the right.) Only exertion of extreme force, such as might actually destroy the sealing ring 52, will be effective to disassemble the valve member A from the valve member B.

When the valve member B is screwed all the way to the left, so that its rear tip portion 34 engages with the bore surface 20, the nozzle will be sealed closed, and no fluid can escape therefrom. At this point, as shown in FIG. 1, the forward tip portion 32 of the valve member A will project out beyond the end of the exit opening 6. As the valve member B is unscrewed and moves to the right as viewed in FIG. 4, the nozzle will be opened and the nature of the stream of fluid emanating therefrom will be determined by the relative location of the forward tip portion 32 with respect to the exit opening 6, in conventional adjustable nozzle fashion. Rotation of the knob or handle 46, which is readily externally acces-

sible at the rear of the nozzle, is translated into axial movement of the nozzle by means of the threaded portions 42 and 26. The left hand end of the valve member B is at all times centered and supported by the projections 38 which ride on the inside of the bore section 22. Axial movement of the valve member B from its sealing position shown in FIG. 1 to its fully open position shown in FIG. 4 is permitted by means of the axially elongated nature of the groove 50 within which the sealing ring 52 rides.

Thus the nozzle of the present invention permits ready adjustment of the nozzle, including close control of the type of fluid stream emanating therefrom, that control being readily effected by the user of the nozzle through rotation of the knob 46 while he holds the nozzle with one hand by means of the body portion 10. Leakage of fluid is effectively prevented by means of the sealing ring 52 and the grooves 30 and 50. The parts are truly minimal in number. The body A and the valve member B may be formed in one piece through suitable manufacturing techniques. The sealing ring 52 may be a standard commercial item. The parts are assembled during manufacture with the utmost in ease and security and the design is such that the parts cannot readily be disassembled or accidentally separated thereafter. Consequently, although the nozzle of the present invention can be manufactured at a very low cost, it will nevertheless function in a manner entirely comparable with, and with equal or superior reliability to, the complicated and expensive devices of the prior art.

While but a single embodiment of the present invention has been here disclosed, it will be apparent that many variations may be made therein, all within the scope of the instant invention, as defined in the following claims.

I claim:

1. An adjustable nozzle comprising a one-piece body having first and second angularly related parts, said first part having a nozzle passage therethrough with first and second openings to the exterior of said nozzle at opposite ends thereof respectively, said first opening defining a fluid exit opening, said nozzle passage having first and second sections of relatively increasing internal size, said first section being located nearer to said first opening than said second section and being located between and spaced from said first and second openings, said second part having a feeding passage therethrough open at one end to the exterior of said nozzle and open at the other end to said first section of said nozzle passage, said feeding passage meeting said nozzle passage at said first section thereof, the inner surface of said body along said first section of said nozzle passage being provided, at least in part opposite said feeding passage and extending to and opening on said second section of said nozzle passage, with an internally threaded portion, the threads opposite said feeding passage being interrupted where said feeding passage meets with said nozzle passage, a unitary valve member movable in said nozzle passage, having a part extending out through said second opening, and having a valve tip movable relative to said first opening to control the escape of fluid therefrom, said valve element having an externally threaded portion engaging directly with the internally threaded portion in said first section of said nozzle passage of said one-piece body, and sealing means operatively engaging said valve member and said nozzle passage for preventing fluid escape at said second opening, said second opening being larger in internal diameter and said first opening being smaller in internal diameter than said first section of said nozzle passage, said second opening being no smaller in internal diameter than said second section of said nozzle passage and communicating therewith without constriction therebetween, whereby said nozzle passage may be formed in said one-piece body by operations all conducted from one end of said nozzle passage and said valve member

may be inserted into and removed from said nozzle passage via said end thereof.

2. The nozzle of claim 1, in which said sealing means operatively engages said nozzle passage at said second section thereof.

3. An adjustable nozzle comprising a one-piece body having first and second angularly related parts, said first part having a nozzle passage therethrough with first and second openings to the exterior of said nozzle at opposite ends thereof respectively, said first opening defining a fluid exit opening, said second part having a feeding passage therethrough open at one end to the exterior of said nozzle and open at the other end to said nozzle passage, said feeding passage meeting said nozzle passage at a point between and spaced from said first and second openings, the inner surface of said body along said nozzle passage being provided, at least in part opposite said feeding passage and extending toward said second opening, with an internally threaded portion, the threads opposite said feeding passage being interrupted where said feeding passage meets said nozzle passage, a unitary valve member movable in said nozzle passage, having a part extending out through said second opening, and having a valve tip movable relative to said first opening to control the escape of fluid therefrom, said valve element having an externally threaded portion engaging directly with the internally threaded portion in said nozzle pas-

sage of said one-piece body, and sealing means operatively engaging said valve member and said nozzle passage for preventing fluid escape at said second opening, said nozzle passage having an internal ring groove adjacent the axial outer end of said second opening and located inwardly therefrom, said valve member having an external ring groove registering with said internal groove, at least one of said grooves being axially elongated, said sealing means comprising a sealing ring received within and sealingly engaging both of said grooves, said internally and externally threaded portions being so axially located as to engage when said external groove on said valve member is axially outwardly out of registration with said internal groove on said nozzle passage, the further threading of said valve member into said nozzle passage bringing said grooves into registration.
